(73) Assignee: **W. C. Bradley Company**, Columbus, GA (US)

(57) **CLAIM**

(**) Term: **14 Years**

The ornamental design of notched handle for cooking utensils, as shown and described.

DESCRIPTION

FIG. 1 is a perspective view showing our new notched handle for cooking utensils;

FIG. 2 is a right side elevational view thereof, the left side being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

The broken lines are for illustrative purposes only and form no part of the claimed design.
